J. A. Cutting,
Spark Arrestor,

No 8077

Patented May 6, 1851.

UNITED STATES PATENT OFFICE.

JAS. A. CUTTING, OF PHILADELPHIA, PENNSYLVANIA.

SPARK-ARRESTER.

Specification of Letters Patent No. 8,077, dated May 6, 1851.

To all whom it may concern:

Be it known that I, JAMES A. CUTTING, of the city and county of Philadelphia and State of Pennsylvania, have invented new and useful Improvements in Spark-Arresters; and I do hereby declare the following to be a full, clear, and exact description of the same, reference being had to the accompanying drawings, making a part 10 thereof, in which—

Figure 1, is a vertical section; Fig. 2, a view of the diaphragm with its curved and inclined planes separating the outer from the inner chambers, and exhibiting a view 15 of the ventilators or air flues in the lower or inclined section. Fig. 3, is a horizontal view of the underside of Fig. 2, showing a series of ventilators or air flues and the curved plane. Fig. 4, is a perspective view 20 of a section showing the combination of the different parts. Fig. 5, is a horizontal view taken at the line a, a , of Fig. 6, showing the air flue, and the entrance of the ventilating tubes. Fig. 6, is a vertical section of the 25 chimney in combination with the ventilating tubes and air chambers.

The same letters in the several figures represent the same parts.

The nature of the first part of my invention consists in arranging upon the outside of the inclined plane at the base of the diaphragm, a series of air flues, extending from the spark chamber through the diaphragm, the mouths of said flues being in the spark 30 chamber, and their exits in the diaphragm, so that the rotary current of steam, &c., through a series of curved flues in said diaphragm will pass over the exits of said air flues, causing a current of air to be drawn 35 from said spark chamber through said air flues in the direction of the current of steam &c, for the purpose of creating a partial vacuum in said spark chamber into which the sparks fall. And in order to effect the 40 deposit of such light particles as may possibly reach the top of the diaphragm the nature of the second part of my invention consists in arranging an air chamber within the diaphragm at the top of the stack, 45 which chamber is ventilated or exhausted, by means of tubes connecting the chamber with the air flue at the bottom of the chamber at the top of the chimney.

To enable others skilled in the art to make 50 and use my invention, I will proceed to de-

scribe the same with reference to the drawings.

At the top of the chimney (A) I place an air chamber (B), over which I place a deflecting cone (C), in the form of a funnel, with the outer edges turned down all around uniformly, to reverberate the steam, gases and particles, and throw them into a series of curved and inclined flues (D) surrounding the air chamber (B) by which a whirling or rotary motion is produced within the diaphragm (O). This diaphragm, is provided with a series of apertures (G). The exhaust steam in passing through the chimney (A) into the air chamber (B) has the effect of drawing a current of air between the curved plane (K) and the chimney (A) through the air flues (F) out of the spark chamber (J).

The air flues (F) are arranged on the outer side of the inclined plane (E) at the base of the diaphragm, and extend from the chamber (J) through the diaphragm (O). The mouths a , of the flues F, are in the spark chamber, J, and their exits e , in the diaphragm (O), the current of air through them being in the direction of the current of steam passing through the inclined flues (D), as shown by the arrows, so as to allow the air to pass out from, and prevent the sparks &c from passing into the spark chamber through said flues F.

At the bottom of the diaphragm (O) under the series of curved and inclined flues (D) is a curved plane (K) and an inclined plane (E). In the inclined plane (E) is placed the series of flues (F) above described. The effect of the passage of the circular current of steam &c within the diaphragm (O) and over the air flues (F,) is to still further exhaust the spark chamber (J) of its air, on the same principle that the spark chamber (J) is ventilated by the passage of steam &c over the air flue (P) (shown by dotted lines in Fig. 6,) at the bottom of the air chamber (B).

The circular current has the tendency by its centrifugal force to throw the particles off in a tangent, against the inner walls of the diaphragm (O) and through the apertures (G) into the outer or spark chamber (J). The deposit of the sparks &c, in the spark chamber (J) is greatly facilitated by the action of the partial vacuum in the spark chamber (J), by which a draft is

occasioned through the apertures (G) of the diaphragm (O) toward said spark chamber (J).

It will be seen that the spark chamber (J) is exhausted of its air, in part, by every pulsation of exhaust steam, consequently between every pulsation there will be a draft toward the spark chamber (J), through the air flue (P) as well as through the apertures (G) of the diaphragm (O). This draft through the air flue (P), toward the spark chamber (J) will have the effect to create a draft upward through the chimney (A) by which the draft of the furnace will be, to a great extent regulated, and the heat correspondingly increased.

Fig. 6, represents the chimney (A), with the air chamber (B) in connection with the pipes (H,) which pass to another air chamber (I), at the top of the stack. The passage of the steam through the chimney (A) tends to draw a current of air through the pipes H, in the same manner in which the ventilation of the spark chamber (J) is effected, the result of which is to exhaust the air chamber (I) of a portion of its air. This air chamber I, is provided with ap-

tures (q), the object of which is to arrest such light particles as may possibly reach the top of the stack, and cause them to pass around again with the view of their being deposited. (L) is the general outlet of the steam and such gases as may be evolved.

Having thus fully described my invention, what I claim therein as new, and desire to secure by Letters Patent is—

1. The air flues (F) in the lower part of the diaphragm (O) constructed in the manner and for the purposes herein described.

2. I claim the pipes or conductors (H) in combination with the air chambers (I) and (B) arranged substantially as herein described.

3. I claim the combination and arrangement of the air flues F, with the air chamber (B), reverberating cone (C), inclined and curved flues (D), for the purpose, and in the manner herein fully set forth and described.

JAMES A. CUTTING.
